UNITED STATES PATENT OFFICE

HENRY L. WRATTEN, OF RACINE, WISCONSIN

BOILER

Application filed May 28, 1928. Serial No. 281,177.

This invention relates to improvements in boilers.

It is one of the objects of this invention to provide an improved boiler in which the 5 hot gases of combustion are utilized to heat a fluid within the boiler in a very efficient and economical manner.

It is a further object of this invention to provide an improved boiler in which the hot 10 gases of combustion are directed through and around the fluid in a circuitous route so that there is a maximum extraction of heat from said gases and a minimum of waste through the chimney.

15 It is a further object of this invention to provide an improved boiler in which the chimney flue is formed with a U-shaped extension surrounding the outside of the boiler and connecting with a chamber below, the 20 gases of combustion being discharged from said chamber into the flue extension and passing out around the boiler to the flue proper, the heat remaining in said gases being thereby utilized to additionally heat the fluid within 25 in the boiler.

It is a further object of this invention to provide an improved boiler which is simple in construction and well adapted for the purpose described.

30 With the above and other objects in view, the invention consists of the improved boiler and all its parts and combinations as set forth in the claims and all equivalents thereof.

In the accompanying drawing, in which 35 the same reference characters designate the same parts in all of the views:

Fig. 1 is a longitudinal section of the improved boiler;

Fig. 2 is a cross section taken on the line 40 2—2 of Fig. 1; and

Fig. 3 is a front end view, parts being broken away.

Referring to the drawing, the numeral 5 designates the boiler generally which has extending within it, at one end, a combustion

chamber 6. Grate members 7 support the fuel, and an ash chamber 8 having a door 9 is positioned below said grate. The combustion chamber is formed with a fuel opening 10 which connects with an opening 11 in the front end of the boiler. The opening 11 is normally closed by a door 12. Spacer rods 4 extend between the walls of the boiler and the walls of the combustion chamber.

At the other end of the boiler is a chamber 13 separated from the rest of the boiler by a partition 14. Tubular members 15, extending through the boiler from the combustion chamber to the chamber 13, conduct the combustion gases to the latter chamber. 60 Rods 14' extend horizontally between the front end of the boiler and the partition 14, and also between the side walls of the boiler.

At an intermediate point in the lower portion of the boiler is a chamber 16, which 65 is separated from the boiler proper by walls 17. The latter chamber is connected with the end chamber 13 by a plurality of tubular members 18. The chamber 16 is provided with a clean-out opening 19 which is normally closed by a cover 20.

One of the novel features of the invention resides in the employment of a chimney flue extension 21 forming a U-shaped discharge passageway 21' which extends around the 70 boiler proper connecting at each side 22 with the lower chamber 16. The top of the passageway 21 is formed with an opening 23 to which the chimney flue 24 is connected. Clean-out openings 25 are provided in the 80 upper portion of the passageway.

The operation of the boiler is as follows: The hot gases formed within the combustion chamber 6 are drawn through the tubular members 15 heating the water in the boiler 85 which surrounds said members. From the tubular members 15 the gases of combustion pass into the end chamber 13 and are then drawn into the tubular members 18. In passing through the latter, the water in the lower 90

portion of the boiler is heated. From the tubular members 18 the gases enter the chamber 16, and then pass to the chimney flue 24 by travelling through the discharge passageway 21' on both sides of the boiler. The novel construction of the passageways and flues accomplishes thorough heating of the water in both the upper and lower portions of the boiler, and also additional heating as the gases pass around the boiler to the chimney flue. The invention therefor provides a means for extracting a maximum amount of heat from the gases of combustion and thus renders the improved boiler both efficient and economical.

15. What I claim is:

1. A boiler comprising an outer casing, a combustion chamber within one end of said casing, a chamber at the other end of the casing, a tubular member connecting the combustion chamber with the end chamber and extending through the boiler for conveying gases of combustion therethrough, an intermediately positioned chamber in a lower portion of the boiler, a tubular member connecting the end chamber with the intermediate chamber and extending through the boiler, and a discharge passageway surrounding a portion of the boiler and connecting with both sides of the intermediate chamber.

30. 2. A boiler comprising an outer casing, a combustion chamber within one end of said casing, a chamber at the other end of the casing, a tubular member connecting the combustion chamber with the end chamber and extending through the boiler for conveying gases of combustion therethrough, an intermediately positioned chamber in a lower portion of the boiler, a tubular member connecting the end chamber with the intermediate chamber and extending through the boiler, and a U-shaped discharge passageway surrounding a portion of the boiler and connecting with both sides of the intermediate chamber.

45. 3. A boiler comprising an outer casing, a combustion chamber extending into said casing at one end, a chamber at the other end of the casing, a plurality of tubular members connecting the combustion chamber with the end chamber and extending through the boiler for conveying gases of combustion therethrough, an intermediately positioned chamber in the lower portion of the boiler, a plurality of tubular members connecting the end chamber with the intermediate chamber and extending through the boiler, and an extension U-shaped in cross section, surrounding a portion of the boiler to form a discharge passageway around said boiler, the lower ends of said extension merging into opposite sides of the intermediately positioned lower chamber.

60. 4. A boiler comprising an outer casing, a combustion chamber within said casing, another chamber in said casing, a tubular member connecting the combustion chamber with

said other chamber and extending through the boiler for conveying gases of combustion therethrough, an intermediately positioned chamber, a tubular member connecting the second mentioned chamber with the intermediate chamber and extending through the boiler, and a discharge passageway surrounding a portion of the boiler and connecting with the intermediate chamber.

65. In testimony whereof, I affix my signature.

HENRY L. WRATTEN.
